DESIGN.

—o—

F. MANKEY.

PANEL.

No. 17,113.

Patented Feb. 15, 1887.

UNITED STATES PATENT OFFICE.

FREDERICK MANKEY, OF WILLIAMSPORT, PENNSYLVANIA.

DESIGN FOR A PANEL.

SPECIFICATION forming part of Design No. 17,113, dated February 15, 1867.

Application filed December 30, 1866. Serial No. 223,032. Term of patent 7 years.

To all whom it may concern:

Be it known that I, FREDERICK MANKEY, of Williamsport, Lycoming county, Pennsylvania, have invented and produced a new and original Design for Panels, of which the following is a specification, reference being had to the accompanying photograph, forming part hereof.

My design consists in the hexagonal elevation A, having inclined or beveled sides B and a flat upper surface, C. Adjacent and having one side parallel to each side of said elevation A are triangular elevations D E F G H I, also having inclined or beveled sides and upper flat surfaces. Between the triangles D and E, F and G, G and H, and I and D, are the quad-

rangular elevations J K L M, also having inclined sides and upper flat surfaces. This design may be repeated upon the surface of the panel.

I claim—

The design for a panel, substantially as herein shown and described, which consists in the hexagonal elevations A, triangular elevations D E F G H I, and quadrangular elevations J K L M, all of said elevations having beveled or inclined sides and flat upper surfaces.

FREDERICK MANKEY.

Witnesses:

C. F. MANKEY,
LEONHARD KNAUSS.
